BROACH SHARPENING MACHINE

Harry H. Gotberg, Detroit, Mich., assignor to
Colonial Broach Company, Detroit, Mich., a corporation of Delaware

Application March 24, 1943, Serial No. 480,303

5 Claims. (Cl. 51—131)

The present invention relates to a broach sharpening machine.

In the past it has been found necessary to sharpen round and surface broaches on two different types of machines—one for each type of broach—because of the differences in the manner in which the grinding wheel must be adjusted and manipulated in sharpening the two types.

The general object of the present invention is to provide a universal broach sharpening machine adapted to sharpen both round and surface broaches.

It is another object of the present invention to provide a single machine which may be employed in sharpening both types of broaches and in which the manipulations required of the operator in sharpening each type of broach are the same as they are in the prior machines.

Other objects and advantages of the invention will become apparent from the following specification, the accompanying drawings and the appended claims.

In the drawings, in which like numerals are used to designate like parts in the several views throughout:

Figure 1 is a fragmentary front view of the machine, showing the machine adjusted to sharpen a round broach;

Figure 2 is a fragmentary view corresponding to Figure 1, showing the machine adjusted to sharpen a flat or surface broach;

Figure 3 is a rear perspective view of the machine corresponding to Figure 1;

Figure 3a is an elevation taken on the line 3a—3a of Figure 3, showing the belt drive with the cover plate removed;

Figure 4 is a transverse section taken on the line 4—4 of Figure 1;

Figure 5 is a longitudinal section through the wheel supporting mechanism, taken on the line 5—5 or Figure 4;

Figure 6 is a fragmentary section taken on the line 6—6 of Figure 4;

Figure 7 is a horizontal section taken on the line 7—7 of Figure 4;

Figure 8 is a fragmentary front elevation of the machine, showing the hand wheels for controlling its operation; and

Figure 9 is a fragmentary transverse section taken on the line 9—9 of Figure 8, showing the gearing for moving the work slide.

Referring to the drawings, and particularly to Figures 1 to 3, the machine comprises a main base 10 having a horizontally movable work slide 11 supported on ways in any suitable manner. The work supporting slide 11 is adapted to support a pair of conventional centers 12 and 13 for rotatably supporting a round broach in the manner shown best in Figure 1. The center 12 is part of a motor driven spindle mechanism indicated gen-

erally at 14, by means of which the center 12 and the dog 15 may be rotated in order to rotate the broach during the sharpening operation. The motor driven spindle unit 14 and the support 16 for the support for center 13 are adjustable along the slide 11 to accommodate broaches of different lengths. The slide 11 may also support a pair of steady rests 17.

When the machine is to be used for sharpening flat or surface broaches, the table is provided with a suitable chuck, such as the magnetic chuck 18, illustrated in Figure 2.

The machine is provided at the rear thereof with a vertical slide 20 guided and supported in suitable ways 21 on the base 10, as best shown in Figures 3 and 7. Vertical slide 20 is hollow and is open at its forward face, as best shown in Figure 4, in order to permit a gear housing 24, which is fixed to the rear wall of the base 10, to project into the slide without interfering with vertical movements of the slide.

As best shown in Figures 4 and 7, the gear housing 24 supports two pairs of worm and worm wheel drive units. One of these units includes the worm 25 mounted upon a hollow shaft 26 journaled in suitable ball bearings 27. The worm 25 meshes with a worm wheel 28 fixed to a vertical shaft 29, which projects downwardly through a boss 30 in the under side of the gear housing 24. In the boss are positioned a pair of bearing sleeves 31 for journaling the shaft. A collar 32 on shaft 29 co-operates with the worm wheel 28, the boss 30 and a pair of roller thrust bearings 32 to hold the shaft 29 against axial movement with respect to the gear housing. The lower end of shaft 29 is threaded into a sleeve 34 positioned within a suitable bearing block 35 fixed to the forward face of the vertical slide 20. As the result of this arrangement, rotation of the shaft 29 will cause the vertical slide to move up or down with respect to the base 10 of the machine.

The second worm wheel unit includes a worm 40 axially aligned with the worm 25 and mounted upon a hollow shaft 41 journaled in suitable roller bearings 42. The worm 40 meshes with the worm wheel 44, fixed to a vertical sleeve 45. The sleeve 45 is journaled in a boss 46 in the under side of the gear housing 24 by means of a pair of bearing sleeves 47. The lower end of the sleeve 45 is provided with a flange 49 which, together with the gear 44, the boss 46 and a pair of ball thrust bearings 48, holds the sleeve against axial movement with respect to the gear housing.

The sleeve 45 is provided with an internal axial splined opening which slidably receives a splined shaft 50. The position of the shaft 50 with respect to the vertical slide 20 is controlled by a lever 52 having a yoke which engages between the flanges of a spool 53 threaded on a reduced portion at the lower end of shaft 50. The spool is

locked in position by means of a nut 54. Lever 52 is fixed to a shaft 55, which projects from the side of the vertical slide 20 and carries a lever 56. Slidably mounted in the end of lever 56 is a handle 57 which is secured to a spring pressed detent 58, adapted to enter a pair of arcuately spaced openings 59 in the side of the vertical slide 20 in order to hold the lever 56 and, consequently, the shaft 55 in adjusted position.

The upper end of the vertical slide 20 is provided with a central hollow cylindrical post 60 surrounding which is an horizontally disposed annular surface 61 adapted to rotatably support a rotary table 64. Secured to the rotary table at its under side is an annular ring 65, which slidably engages the annular surface 61. The rotary table 64 is provided with a vertical opening 66 in which the cylindrical projection 60 of the vertical slide is journaled. As a result of this arrangement, it is apparent that the table is supported for rotation with respect to the vertical slide 20 about a vertical axis.

The upper end of the previously described vertical shaft 55 projects through the cylindrical projection 60, and a sleeve 68 journaled on the shaft 55 likewise projects through the cylindrical projection 60. The upper end of the sleeve 68 is provided with a flange 69 which fits a recess in the upper surface of the table; and the lower end of the sleeve 68 is provided with a nut 70 threaded on the sleeve. The nut 70 takes the form of a worm wheel that meshes with a worm 71 fixed to a horizontal shaft 72 which projects through one side of the vertical slide 20 and carries a handle 73 by means of which the shaft may be manually rotated. It will be apparent that, on rotation of the handle 73 in the proper direction, worm wheel 70 will be threaded upon the sleeve 68. Since the upper surface of the worm wheel 70 bears against a downwardly projecting boss 75 in the upper end of the vertical slide 20, this threading action will clamp the rotary table 64 against the annular surface 61. This clamping action may be adjusted to such a degree that the rotary table cannot turn.

The upper end of shaft 55 carries a pinion 80 adapted to mesh with a rack 81 fixed in any suitable manner to a horizontal slide 82. As best shown in Figures 4 and 5, the horizontal slide 82 is supported upon a pair of roller chains 83, each of which surrounds a horizontal laterally projecting rib 84 formed on the upper portion of the rotary table 64. The ribs 84 extend parallel to each other and lie on opposite sides of the cylindrical projection 60. Each roller chain forms a complete closed loop, with the result that one side of the loop overlies the rib 84 while the other side of the loop lies under the rib 84. The upper side of each rib 84 is provided with a longitudinal race 87 having a central upstanding rib adapted to support the rollers 88 of the chain 83. A similar race 89 is secured to the under side of the horizontal slide 82, and engages the upper sides of the rollers 88. As the result of this arrangement, the upper portion of the chain loop supports the horizontal slide 82 with reference to the rotary table 64, and the idle portion of the chain is returned below the rib 84.

It will be observed that, when shaft 55 is elevated by manipulation of handle 57, the gear 80 on the upper end of the shaft will be raised out of engagement with the rack 81. At such time the horizontal slide will be free to roll horizontally upon the rotary table. A handle 89, shown best in Figures 1 and 3, is provided in order that

the operator may readily move the horizontal slide back and forth on the roller chain, as is required in sharpening surface broaches. The handle 89 for moving the horizontal slide 82 backward and forward is connected to a shaft 106 journaled in the horizontal slide 82. The shaft 106 extends through a vertically sliding block 107 having an upwardly projecting threaded stud 108. A nut 109, threaded on the stud 108 and bearing against a washer 110, may be tightened to pull the sliding block upwardly and hence clamp the shaft 106 and, consequently, the handle 89 against rotation. This means is provided to adjust the position of the handle 89 to suit the convenience of the operator.

As best shown in Figure 2, a pair of adjustable stops 90 are secured to the side of the horizontal slide 82. The stops 90 are adjustable longitudinally of the slide by means of a T-slot 91 and are held in adjusted position in the usual manner, as by nuts 92. The adjustable stops 90 are adapted to co-operate with a stationary stop 93 fixed to the rotary table. The stop 93 includes a pair of spring pressed plungers 94 projecting in opposite directions and adapted to co-operate respectively with the stops 90 to resiliently limit horizontal sliding movement of the slide 82.

A rotary wheel support 95 is journaled on the forward end of the horizontal slide 82 for rotation with respect to the slide about a horizontal axis. The wheel support 95 has a rearward cylindrical projection 96 journaled within a cylindrical recess 97 in the forward end of the horizontal slide 82. A stud 98, threaded into the wheel support 95 and provided with a pair of nuts 99, holds the wheel support in position, with the annular surface 101 on the forward face of the horizontal slide 82 slidably engaging an annular ring 102 fixed to the wheel support 95. The rotary wheel support 95 may be held in adjusted position by any suitable means, such as a set screw connected to a handle 104, shown in Figure 3. The set screw is threaded through the side wall of the horizontal slide 82 and into engagement with the cylindrical projection 96 of the rotary wheel support 95.

The rotary wheel support 95 contains an electric motor 112 having a shaft 114 journaled in suitable bearings, not shown, and a grinding wheel shaft 115 extending parallel to the motor shaft 114 and journaled in anti-friction bearings 116. A grinding wheel 117 is mounted on the projecting end of the shaft 115.

As best shown in Figure 3a, which is a side elevation of the rotary wheel supporting member, the grinding wheel shaft 115 is driven from the motor shaft 114 by means of a pair of pulleys 120 and 121 connected by a belt 122. The pulleys are removably secured upon their respective shafts by means of nuts 123 and 124. The belt and pulleys are enclosed within a removable housing section or cover 125. The belt drive is employed in order to permit change in the speed ratio between the two shafts. When sharpening very small diameter round broaches, it is necessary to employ a grinding wheel of very small diameter to avoid interference with the tooth face. Consequently, in order to obtain the most efficient cutting speed for the small grinding wheel it is necessary to drive the grinding wheel shaft at a higher rate of speed than when employing a larger wheel. The necessary change in speed ratio may be readily accomplished by changing the pulleys on the shafts 114 and 115.

In Figures 4 and 7 to 9, the means for selec-

tively operating the worm wheels 28 and 44 is best shown. Referring to Figure 7, the left-hand end of the hollow shaft 26 is formed as a dog clutch having two diametrically opposed recesses 130 (only one of which appears in Figure 7) adapted to co-operate with a dog clutch ring 131 fixed, by means of a pin 132, to a shaft 133 which is journaled within the hollow shafts 26 and 41. Similarly, the right-hand end of the hollow shaft 41 is provided with a dog clutch having two diametrically opposed recesses 135 adapted to co-operate with corresponding teeth on the opposite side of the dog clutch ring 131. The parts are shown in Figure 7 in the position in which the dog clutch ring 131 is engaged with the hollow shaft 41, in which position rotation of shaft 133 effects rotation of the worm 40 and worm wheel 44 without rotating worm 28.

When the shaft 133 is shifted axially to the right, as viewed in Figure 7, the teeth of the dog clutch ring 131 engage in the recesses 130 of the hollow shaft 26 and similarly drive the worm 28 and the worm wheel 28 without rotating worm 40. The right-hand end of the shaft 133 is secured, by means of a tapered pin 136, to a tubular shaft 137 which, in turn, is similarly connected by pin 138 to a shaft 139, which projects through a cover plate 140 associated with an opening in the front face of the base 10. The outer extremity of shaft 139 carries a hand wheel 141. Shaft 139 is provided with a pair of annular grooves 143 and 144 so positioned that when the shaft is in its innermost position, shown in Figures 4 and 7, the outer groove 144 is just inside the inner surface of the cover plate 140. The grooves 143 and 144 are adapted to cooperate with a spring pressed latch slide 146, best shown in Figures 4 and 6. The slide 146 is provided with a reduced extremity 147 adapted to fit within either the groove 143 or 144, and in Figure 6 the extremity 147 is shown engaging in the groove 144. Latch slide 146 is slidable within a U-shaped bracket 150 secured to the inner face of cover plate 140 in any suitable manner, as by cap screws 151. A spring 152, received within a recess in the bracket 150, bears against a pin 153 secured to the latch slide 146, thus normally urging the latch slide into engagement with one of the recesses 143 or 144. The latch slide is provided with a notch 155 adapted to receive the rounded extremity of a dog 156 secured to a rotary stub shaft 157 journaled in a boss 158 formed on the cover plate 140. A handle 159 is secured to the outer extremity of the shaft 157 for operating the shaft.

When it is desired to shift the shaft 133 and, consequently, the shaft 133 and dog clutch ring 131 from the position shown in Figure 7 to the position in which the dog clutch engages the hollow shaft 26, handle 159 is rotated in a direction to retract the latch slide 146 from notch 144, whereupon the operator may, by pulling the hand wheel out, shifts the shafts and clutch member. Upon completion of the shifting operation and release of handle 159, spring 152 will cause the latch slide 146 to engage in notch 143 of shaft 139 and thus hold the parts in the new position.

It will be observed that, as best shown in Figure 7, the cover plate 140 is provided with a hollow annular projection 161, and the hand wheel 70 is provided at its inner side with an annular ring 162 adapted to telescope within the projection 161. When the hand wheel and shaft 139 are shifted to their outer position, the annular ring 162 lies just outside of the extremity of annular

projection 161 and a suitable scale may be provided on the ring 162 to cooperate with a marked point on the projection 161 and thus indicate the position to which the hand wheel 141 must be turned to raise or lower the vertical slide 20 until the axis of the grinding wheel is on the same level as the axis of a round broach mounted in the lathe centers. It will be observed that when the hand wheel is shifted to its outer position, it drives through worm 25 and worm wheel 28 the screw 29 which controls the elevation of the vertical slide 20. The dog clutch 131 has only two teeth and, consequently, can engage in only two positions, 180° apart. A rotation of the hand wheel through 180° will shift the vertical slide sufficiently to make the error in vertical position easy to observe. Accordingly, the scale on ring 162 may have two zero points 180° apart or, if only one is employed, the operator will be able to observe when the zero reading is displaced 180° and may, by disengaging the clutch 131 from hollow shaft 26, rotate the hand wheel 141 through 180° and re-engage the clutch.

The means for reciprocating the work table 25 is best shown in Figures 4, 7 and 9. Immediately to the right of the hand wheel 141, the base 10 is provided with an opening adapted to receive a gear housing 165 which is provided with a flange 166 corresponding in shape to the cover plate 140. Flange 166 is secured to the front of the base 10 in any suitable manner, as by bolts 167, and similar bolts are employed to secure the cover plate 140 in position.

A shaft 169 is journaled in the housing and projects therefrom at the front to receive a hand wheel 170. The inner end of shaft 169 carries a pinion 171 which meshes with a gear 172 on a countershaft 173 likewise journaled in the housing 165. Countershaft 173, in turn, carries a pinion 174 which meshes with a gear 175 on shaft 176 likewise journaled in the housing. Shaft 176, in turn, carries a pinion 177 which meshes with a rack 178 fastened by means of cap screws 179 to a rib 180 formed on the under side of the table 11. As a result of this construction, rotation of the hand wheel 170 shifts the table 11 transversely of the machine.

The operation of the machine is as follows: When it is desired to sharpen round broaches, 50 the broach is mounted in the centers, as shown in Figure 1. Steady rests are placed in position in the event that the broach is long enough to require support intermediate its ends. Latch handle 159 is then shifted to the release position and hand wheel 141 is pulled out in order to cause clutch ring 131 to engage hollow shaft 26. The hand wheel is then rotated until the axis of the grinding wheel is on the same horizontal level as the axis of the broach, that point being indicated by the scale on the annular ring 162. Thereupon, the latch handle 159 is again released and hand wheel 141 pushed inward to cause engagement between the clutch ring 131 and the hollow shaft 41 to effect a driving connection 60 between the hand wheel 141 and the horizontal table 82. The rotating table 64 is then swung until the plane of the grinding wheel corresponds to the angle made by the face of the broach teeth, and it is clamped in that position by manipulation of handle 73. The rotary wheel support is fixed in the position in which the axis of the grinding wheel spindle 115 lies in a horizontal plane. The machine is then conditioned to perform the sharpening operation.

The sharpening operation is carried out in the

usual manner by manipulating the hand wheels 141 and 170. Thus the operator, with one hand on each hand wheel, rotates the hand wheel 170 until the grinding wheel 117 is in alignment with the front face of the tooth to be sharpened, whereupon the wheel 141 is rotated to feed the wheel into the tooth space, thereby removing the thin layer on the front face of the tooth. It will be observed that an accurate control of the position of the grinding wheel relative to the tooth space is provided by the two hand wheels. During the grinding operation it is to be understood, of course, that the broach will be rotated by the driven spindle unit 14.

In order to sharpen surface broaches, lever 56 is shifted to elevate shaft 50 and thereby disengage pinion 89 from rack 81, as shown in dotted lines in Figure 5. Hand wheel 141 is then pulled out to engage the clutch ring 131 with the hollow shaft 26. The rotary table 64 is turned until the path of movement of the horizontal slide 82 is parallel to the broach teeth. In most cases the broach teeth will run perpendicular to the slide 11 and, consequently, the table will be rotated until the slide 82 is perpendicular to the slide 11. It will then be clamped in that position. The rotary wheel support 95 is then rotated about the axis of stud 98 until the plane of the grinding wheel 117 lies in the plane of the front faces of the broach teeth, as best shown in Figure 2. After these adjustments are made, the hand wheel 141 is manipulated to adjust the vertical slide 20 until the grinding wheel 117 is at the proper height to cut to the root of the teeth. The machine is then in condition to perform the sharpening operation.

The sharpening of surface broaches is effected by manually reciprocating the roller mounted horizontal slide 82, the operator grasping the handle 89 for that purpose. In this connection, the adjustable stops 90 are set to limit the reciprocation of the slide 82 at each end of the broach teeth. Between each manual reciprocation of the horizontal slide 82, the operator rotates the hand wheel 170 to properly align the grinding wheel 117 with the tooth to be sharpened.

It will be observed that in accordance with the present invention there is provided a simple machine which may be effectively used to sharpen both round and flat broaches. An important feature of the machine resides in the fact that the hand wheel 170 for operating the work slide 11 is in the same position with respect to the hand wheel 141, which controls either the vertical slide 20 or a horizontal slide 82, as it is to the hand wheel which controls the horizontal slide on conventional round broach sharpening machines, and the wheel 170 is in the same position with respect to the handle 89 and the hand wheel 141 as it is to the handle and the corresponding hand wheel for controlling the vertical slide on conventional flat broach sharpening machines. This is advantageous because broach sharpening is a highly skilled operation and the workmen are accustomed, through years of experience, to more or less conventional positions for the primary control handles and hand wheels, those conventional positions having been found most desirable as a result of long experience.

While only one form of the invention is shown and described, it is apparent that modifications are available within the spirit of the invention and within the scope of the appended claims.

What is claimed is:

1. In a broach sharpening machine, a rotary grinding wheel, a machine base, means mounting

the grinding wheel on the base for rectilinear movement both in a horizontal path perpendicular to the wheel axis and in a vertical path and rotary movement about two axes parallel, respectively, to the paths of rectilinear movement, separate driving mechanisms for effecting controlled rectilinear movement in each of said paths, a manually operated shaft, and means for selectively connecting said shaft to said driving mechanisms.

2. In a broach sharpening machine, a rotary grinding wheel, a machine base, means mounting the grinding wheel on the base for rectilinear movement both in a horizontal path perpendicular to the wheel axis and in a vertical path and rotary movement about two axes parallel, respectively, to the paths of rectilinear movement, separate means for effecting controlled rectilinear movement in each of said paths, said last named means including a shaft, a hand wheel for operating the shaft, a pair of driven members freely journaled on said shaft and adapted, respectively, to effect movement of said wheel in said paths, and means for selectively clutching said driven members to said shaft.

3. In a broach sharpening machine, a rotary grinding wheel, a machine base, means mounting the grinding wheel on the base for rectilinear movement both in a horizontal path perpendicular to the wheel axis and in a vertical path and rotary movement about two axes parallel, respectively, to the paths of rectilinear movement, separate means for effecting controlled rectilinear movement in each of said paths, said last named means including an axially shiftable shaft, a hand wheel for operating the shaft, a pair of driven members freely journaled on said shaft and adapted, respectively, to effect movement of said wheel in said paths, and means operable on axial shifting of said shaft for selectively clutching said driven members to said shaft.

4. In a broach sharpening machine, a base, a vertically movable slide mounted on the base, a rotary table journaled on said slide for movement about a vertical axis, a horizontally movable slide mounted on said table, a grinding wheel support rotatably mounted on said horizontally movable table for movement about an axis perpendicular to said vertical axis, a horizontal shaft journaled on said base and a vertical shaft journaled on said base concentric with said vertical axis, a driving connection between said horizontal shaft and said concentric vertical shaft, a disengageable driving connection between said concentric vertical shaft and the horizontally movable table, and manual means for operating said horizontal shaft.

5. In a broach sharpening machine, a base, a vertically movable slide mounted on the base, a rotary table journaled on said slide for movement about a vertical axis, a horizontally movable slide mounted on said table, a grinding wheel support rotatably mounted on said horizontally movable table for movement about an axis perpendicular to said vertical axis, a horizontal shaft journaled on said base and a pair of vertical shafts journaled on said base, one of said vertical shafts being concentric with said vertical axis, a selectively operative driving connection between said horizontal shaft and said vertical shafts, a driving connection between said concentric vertical shaft and the horizontally movable table, a driving connection between the other vertical shaft and the vertically movable table, and manual means for operating said horizontal shaft.

HARRY H. GOTBERG.
